WILLIAM E. HASKELL, OF BRATTLEBORO, VERMONT, ASSIGNOR TO ESTEY ORGAN COMPANY, OF BRATTLEBORO, VERMONT, A CORPORATION OF VERMONT.

PNEUMATIC SWITCH.

1,297,687.

Specification of Letters Patent.

Patented Mar. 18, 1919.

Original application filed January 22, 1917, Serial No. 143,750. Divided and this application filed June 24, 1918. Serial No. 241,526.

To all whom it may concern:

Be it known that I, WILLIAM E. HASKELL, of Brattleboro, in the county of Windham, in the State of Vermont, have invented a new and Improved Pneumatic Switch, of which the following is a specification.

This application is a division of application filed January 22, 1917, Serial Number 143,750, for improvements in organs. 10 While the pneumatic switch herein set forth is particularly designed for use in organs it may be employed in other organizations wherein it is useful to open and close an electric circuit by a pneumatically actuated switch.

One embodiment of the improved pneumatic switch is illustrated in the accompanying drawings wherein—

Figure 1 is a cross section of a tube bar such as is employed in an organ having an electro pneumatic action, such tube bar being shown equipped with one of the pneumatic switches in its normal open position. Fig. 2 is a vertical section of the pneumatic switch on a larger scale than shown in Fig. 1, the switch being shown in position to close the electric circuit controlled thereby. Fig. 3 is a cross section in the plane indicated by the line 3—3 in Fig. 2.

30 The switch includes an inverted cylindrical metallic cup A, preferably of copper. The lower open end of the cup fits upon a stationary piston B, having an easy sliding fit thereupon. The piston B is composed of 35 plumbago, thereby insuring a non-corrodible organization which permits the cup to readily slide while maintaining a sufficiently close fit to avoid objectionable air leakage. The piston B has a reduced foot 4, which is 40 socketed into the top of a tube bar C. This tube bar has an air passage 5. If air under pressure enters the channel 5, it passes through a lateral port 6, into the hollow central bore 7, of the piston B and thence 45 into the upper end of the cup A. Thereupon the cup rises. Then, when the air pressure in the passage 5, is vented, the cup A drops by gravity.

50 This up and down pneumatically controlled movement of the cup A is utilized to make and break an electric circuit. Soldered to one side of the cup is a fine coiled wire 8, which is connected at its other end to

a fixed metallic rod 9, constituting one terminal of an electric circuit. This fine coiled wire extends at right angles to the movement of the cup so that it offers no sensible resistance to such movement. The cup at its top has a central non-corrodible contact button, preferably of platinum, which is immediately beneath the outer end of a resilient metallic spring contact D, which is secured at its other end to a fixed bus-bar E. This contact D constitutes the opposite terminal of the circuit which includes the rod 9. The free end of this resilient terminal is in line with the bore 7.

Normally there is no excess air pressure in the passage 5, and, consequently the cup A occupies its lower position shown in Fig. 1 and below and out of contact with the spring terminal D. Consequently the electric circuit is normally broken. When, however, compressed air is admitted into the passage 5, the cup A is lifted, as shown in Fig. 2, thereby making contact with the terminal D, and hence closing the electric circuit.

The extent of the rise and fall of the cup A may be regulated by the illustrated adjusting devices. A hand turned rod F screws into the bottom wall 11, of the tube bar and passes centrally through the port 6, and the bore 7. At its upper end it carries a stop G, having a felt pad 12, on top. The upper part 13 of the central bore is enlarged to accommodate the stop. The extent of downward movement of the cup A, is thus determined by the position of the adjustable padded stop G, since the cup rests thereon when in its lowest position. The upward movement of the cup is limited by the yielding terminal D. The extent of vertical movement of the cup need only be just sufficient to make and break the electric circuit, so that a minimum quantity of air is required to lift the cup. Hence the pneumatic switch is sensitive and prompt, these being characteristics which are especially important in an organ action.

100 Another characteristic which is important in an organ action is that the switches should be noiseless. The descent of the cup A is rendered noiseless by the felt padding 12, on the stop G. When the cup rises 105 to close the electric circuit it abuts against

the resilient terminal D, which yields under the impact of the cup thereby reducing the noise to a minimum.

Fig. 1 illustrates a tube bar C having a large number of air passages 5, and hence of the metallic switches, such as is set forth in the aforesaid parent application Serial Number 143,750, in connection with a tracker over which a perforated note sheet 10 travels. Each aperture in the tracker communicates by means of a tube 14, with one of the air passages 5, in the tube bar C. Hence, when an aperture in the tracker is uncovered by a hole in the note sheet air 15 flows into the corresponding air passage 5, and the corresponding pneumatic switch is closed. In order to protect the pneumatic switches from the dust and to muffle the same so as to contribute to noiselessness 20 they are inclosed by a cover H, resting on the top of the tube bar C. In the event that the cup A, is lifted by compressed air admitted into the air passage 5, the cover H does not fit tight on the tube bar so that the 25 sensitivity of the cup is not interfered with by leakage of air between the cup and the piston.

I claim—

1. A pneumatic switch mechanism having, a bus-bar E, a resilient terminal D, a fixed terminal 9, a fixed plumbago piston B, having a central bore 7, in line with the free end of said resilient terminal and a tube bar C, having an air passage 5, and a 30 port 6, between said passage and bore, in combination with a rising and falling inverted metallic cup sliding upon said piston with an easy fit and adapted when lifted to contact with the free yielding end of said 35 resilient terminal, a coiled wire 8, connected at opposite ends to said cup and said fixed terminal respectively, and an adjusting rod 40 F, screwing into said tube bar extending into the piston and having on its upper end 45 a padded stop to limit the descent of the cup.

2. A pneumatic switch mechanism having, a bus-bar, a resilient terminal, a fixed terminal, a fixed plumbago piston having a 50 central bore and a tube bar having an air passage and a port between said passage and bore, in combination with a rising and falling inverted metallic cup sliding upon said piston with an easy fit and adapted when

lifted to contact with the free yielding end 55 of said resilient terminal, and a coiled wire connected at opposite ends to said cup and said fixed terminal respectively.

3. A pneumatic switch mechanism having a resilient terminal, and a fixed plumbago 60 piston having a central bore, in combination with a metallic cup sliding upon said piston and adapted when moved to contact with the free yielding end of said resilient terminal, and means for admitting air into 65 said cup through the bore of said piston.

4. A pneumatic switch mechanism having a resilient terminal, and a fixed piston with a bore; in combination with a metallic cup 70 sliding upon said piston and adapted when moved to contact with the free yielding end of said resilient terminal, and means for admitting air into said cup through the bore of said piston.

5. A pneumatic switch mechanism having, 75 a resilient terminal, a fixed terminal, and a piston, in combination with a metallic cup sliding upon said piston and adapted when moved to contact with the free yielding end of said resilient terminal, and a 80 coiled wire connected at opposite ends to said cup and said fixed terminal respectively.

6. A pneumatic switch mechanism having a resilient terminal, and a fixed piston having a bore in combination with a metallic 85 cup sliding upon said piston and adapted when moved to contact with the free yielding end of said resilient terminal, and an adjusting rod extending through said bore and having a padded stop to limit the move- 90 ment of the cup.

7. A pneumatic switch mechanism having a fixed piston, in combination with a cup 95 sliding upon said piston, and an adjustable padded stop located within the cup to limit the downward movement of the cup, and means for admitting air into the interior of the cup above the piston.

8. A pneumatic switch mechanism having a resilient terminal and a piston, in combination with a cup sliding upon said piston and adapted when moved to contact with the free yielding end of said resilient terminal, and means for admitting air into the 100 interior of the cup above the piston. 105

In witness whereof I have hereunto signed my name.

WILLIAM E. HASKELL.
